UNITED STATES PATENT OFFICE

2,518,793

CRYSTAL MOUNTING

Dan W. Keller, Chicago, Ill., assignor of one-half
to Helen Keller

Application April 10, 1944, Serial No. 530,278

10 Claims. (Cl. 171—327)

1

This invention relates to crystal mountings and more particularly to an electrode construction for mounting and supporting a crystal.

Heretofore crystals have been mounted between stainless steel plates cut to substantially the same size and shape as crystal with its corner portions raised and ground or lapped to fit evenly against the crystal surface. The electrical activity of crystals mounted in this manner changes materially in accordance with temperature changes and according to quite erratic curves. It is believed that this change in activity is due to the changing points of engagement between the electrode and crystal resulting from different temperature coefficients of expansion of the crystal and of the electrode material.

It is one of the objects of the present invention to provide a crystal mounting in which the crystal maintains a substantially uniform activity over a wide range of temperatures.

Another object of the invention is to provide an electrode for use in crystal mountings which has substantially the same coefficient of expansion as the crystal to be mounted.

Still another object of the invention is to provide an electrode formed of a non-metallic body having a conductive covering to engage the crystal. In a preferred construction, the electrode itself is formed of a crystal covered by a thin sheet of metal.

The above and other objects and advantages of the invention will be more readily apparent from the following description when read in connection with the accompanying drawings, in which—

Figure 1 is a side elevation of an electrode constructed according to the invention;

Figure 2 is a section through a crystal mounting;

Figure 3 is a plan view of an electrode; and

Figure 4 is a section on the line 4—4 of Figure 3, showing an alternative construction.

According to the invention a standard crystal as indicated generally at 10 in Figure 2, which may be of rectangular shape, is supported between a pair of electrodes 11 which may be pressed against the crystal by springs or the like. The electrodes preferably have raised portions adjacent their corners to engage the opposite faces of the crystal.

According to the present invention the electrodes 11 are formed by non-metallic bodies 12 of substantially the same size and shape as the crystal to be mounted and which are made of material whose temperature coefficient of expansion is substantially the same as that of the

2

crystal 10. Various types of materials are suitable for this purpose including certain ceramics and plastics which may be selected to have the desired coefficient of expansion. Preferably, however, the body 12 is of the same material as the crystal 10 and may be for example, a cut crystal which has been rejected for some flaw. The non-metallic body 12 is covered by a thin conductive covering 13 extending over its entire surface. 10 Various types of coverings may be employed but I prefer to use a thin sheet of metal either sprayed or plated directly on to the body or in the form of a metal foil covering the body and engaging it uniformly over its surface. At the corners on at least one side of the body, a double thickness of covering is provided as indicated at 14 forming raised portions to engage the opposite faces of the crystal 10. Preferably the portions 14 are ground or lapped to engage the crystal evenly.

With electrodes of this type mounting the crystal as shown in Figure 2, the points of contact between the electrodes and the crystal will be the same under all temperature conditions since expansion of the active crystal 10 will be identical with the expansion of the crystal bodies 12. Therefore, the activity of the crystal 10 will be uniform throughout a wide temperature range.

Since the electrodes can be formed largely of scrap material they can be made inexpensively and will provide uniform mountings for the active crystals.

In the alternative construction shown in Figure 4, the raised corner portions indicated at 14' are formed by grinding or cutting the body 12 to the desired shape with its corner portions raised and uniformly plating or coating its entire surface. The final shape is the same in this construction as in Figure 1 but the covering operation is somewhat simplified. In operation the electrode of Figure 4 functions in the same manner as described above.

While one embodiment of the invention has been shown and described herein in detail it will be understood that this is illustrative only and is not intended as a definition of the scope of the invention, reference for thus purpose being had to the appended claims.

What is claimed is:

1. In a crystal mounting in combination a crystal, an electrode comprising a flat body of non-metallic material having a temperature coefficient of expansion substantially the same as that of the crystal to be mounted, and a conductive covering over the body engaging the crystal.

2. In a crystal mounting in combination a crystal, an electrode comprising a flat body of non-metallic material having a temperature coefficient of expansion substantially the same as that of the crystal to be mounted, and a thin metal covering over the body engaging the crystal.

3. In a crystal mounting in combination a crystal to be mounted, an electrode comprising a flat crystal of substantially the same size and shape and material as the crystal to be mounted and a conductive covering over said flat crystal engaging the crystal to be mounted.

4. In a crystal mounting in combination a crystal to be mounted, an electrode comprising a flat crystal of substantially the same size and shape and material as the crystal to be mounted and a thin metal covering over said flat crystal engaging the crystal to be mounted.

5. In a crystal mounting in combination, a crystal to be mounted, an electrode comprising a flat crystal of substantially the same size and shape and material as the crystal to be mounted and a conductive covering over said flat crystal to engage the crystal to be mounted, said covering being thicker at spaced points adjacent its periphery than over the remainder of its surface to provide raised portions to engage the crystal to be mounted.

6. In a crystal mounting in combination, a crystal to be mounted, an electrode comprising a flat non-metallic body of substantially the same size and shape as the crystal to be mounted, said body being thicker at spaced points adjacent its periphery than over the remainder of its area, and a conductive covering of substantially uniform thickness over the body.

7. In a crystal mounting in combination, a crystal to be mounted, an electrode comprising a flat crystal of substantially the same size and shape and material as the crystal to be mounted,

said flat crystal being thicker at spaced points adjacent its periphery than over the remainder of its area, and a conductive covering of substantially uniform thickness over the flat crystal.

8. An electrode for piezoelectric crystals, said electrode comprising a crystal substantially matching in size and cut the piezoelectric crystal to which it is to be applied and having at least one face thereof covered with electrically conductive material.

9. An electrode for piezoelectric crystals, said electrode comprising a platelike core of non-conductive material having a coefficient of thermal expansion substantially matching that of the piezoelectric crystal with which it is to be used and having at least one face thereof covered with electrically conductive material.

10. An electrode for piezoelectric crystals, said electrode comprising a generally rectangular plate-like core of crystalline quartz wrapped in a thin metal foil which is electrically conductive, and additional layers of material fixed to the corner portions of one face of the wrapped core to constitute feet for the same.
